UNITED STATES PATENT OFFICE.

FRANK A. LUNDQUIST, OF CHICAGO, ILLINOIS, ASSIGNOR, BY MESNE ASSIGNMENTS,
TO HENRY S. CONRAD, TRUSTEE.

SELECTOR SWITCH AND CONNECTION.

Application filed August 21, 1918, Serial No. 250,873. Renewed April 19, 1923.

To all whom it may concern:

Be it known that I, FRANK A. LUNDQUIST, a citizen of the United States of America, and a resident of Chicago, county 5 of Cook, and State of Illinois, have invented certain new and useful Improvements in Selector Switches and Connections, of which the following is a specification.

My invention relates to selector switches 10 and connections therefor, and has for its object improvements in the construction and operation of automatic telephone exchanges.

In the accompanying drawings—

Fig. 1 is a side elevation of the switch; 15 Figs. 2, 3 and 4 are sections on lines correspondingly marked on Fig. 1;

Figs. 5, 6, 7 and 8 are details of parts of the switch;

Fig. 9 is a section of a typical pneumatic 20 motor of which there are several of different sizes in the switch;

Fig. 10 is a section of the valve arrangement used in controlling the admission of air to the motor; and

Fig. 11 is a diagram of the switch and so 25 much of the electrical connections as is necessary to an understanding of the present invention.

Referring to Fig. 9, the motor used is composed of a stationary standard 15 having an axial opening 16, and a tube 17 which fits over and slides on the standard 15. A pipe 18 admits compressed air between the top of the standard 15 and the closed head of 30 the tube 17. When this occurs the tube 17 rises and serves to move any object connected to it. When the admitted air is permitted to escape, the tube 17 returns to normal position by the action of gravity or spring.

40 There are four motors of this type in the present switch. They all operate on the same principle, but differ from each other in details. They will be referred to by characters applied to the moving tube.

45 In Fig. 10 there is shown a casing 19 in which are valves 20 and 21. The valve 20 normally rests on its seat and prevents compressed air flowing in the direction indicated by the arrows. Valve 21 has a projecting stem 22 adapted to be engaged by an armature lever 23 or by any other device to lift said valve and press it against its seat. The valves have stems 24 and 25 projecting toward each other and so arranged

that if armature 23 lifts valve 21 to its seat, 55 valve 20 will be lifted from its seat and permit air to flow to pipe 18, which is the same pipe as that shown in Fig. 9. In other words, when an armature lifts the valves in a casing like 19, compressed air 60 flows thru a pipe like 18 to operate a motor like 17. When the armature falls, the air in the motor is permitted to escape by passing around valve 21 and its stem to outside space. The valves in this switching mechanism will be referred to by the casings which 65 contain them.

The frame of the switch is composed of a bottom bar 26, a top bar 27, and end bars 28 and 29. Near the central part of this 70 frame is a vertically movable motor 30 supplied with compressed air thru a pipe 31 and controlled by valves in casing 32. The motor 30 has on it a rack 33 adapted to be engaged by a pawl 34 on the rock shaft 35. 75 The teeth of rack 33 are so arranged that the pawl 34 will support the motor 30 in its elevated position after the air which moves it has been permitted to escape.

Also on motor 30 is another rack 36 having 80 its teeth facing in the opposite direction from those of rack 33. A pawl 37 on rock shaft 38 is adapted to engage the teeth of rack 36 to stop the upward movement of motor 30 under the action of compressed air. 85 A spring 39 acts on pin 40 in pawl 37 to normally hold said pawl from engagement with rack 36.

The motor 30 and associated parts are carried in a frame 41 which is secured to the 90 outer end of a horizontal motor 42. The motor 42 is operated by compressed air coming thru pipes 43 and 44 from valve casing 45. The valve in casing 45 is operated by an arm 46 on the rock shaft 38.

95 On the motor 42 is a rack 47 which engages a gear 48 on a shaft 49 supported in the framework of the switch. On the shaft 49 with gear 48 is an escape wheel 50 controlled by escape lever 51. The lever 51 is connected to the armature 52 of the magnet 53. When compressed air is admitted to motor 42 by the operation of the valve in casing 45, and impulses flow thru the magnet 53 to attract its armature, the frame 41 with 100 motor 30 is moved step by step to the right. In this movement the pawls 34 and 37 slide on the square parts of the shafts 35 and 38. 105

The roller 54 running on track 55 supports the weight of the parts on the outer end of the motor 42.

Secured to the top of motor 30 are arms 56 and 57, and on these arms are insulated wipers 58, 59, 60 and 61 adapted to engage bank contacts shown in the upper part of Fig. 11. When motor 42 and magnet 53 act to move motor 30 to the right, the wipers are advanced step by step to successive positions under vertical rows of contacts, and then when motor 30 acts, the wipers, are moved upward to successive engagement with contacts in pre-selected rows.

Pivoted to a bracket on the end bar 28 (Fig. 5) is an arm 62 which carries a roller 63 arranged to be engaged by the teeth of the escape wheel 50 when that wheel rotates. When such engagement occurs the teeth of wheel 50 vibrate arm 62 to open and close the adjacent contact springs 64 and 65. When the motor 42 is in its normal position, a pin 66 on said motor engages arm 62 to lift roller 63 clear of wheel 50 and hold springs 64 and 65 in electrical connection with each other. But when motor 42 moves to advance the wipers, the pin 66 leaves the arm 62 and roller 63 falls to engagement with the teeth of wheel 50.

Pivoted at 67 (Fig. 1) on motor 42 are two pawls 68 and 69 arranged to engage a stationary ratchet 70 bolted to end bar 28. A projection 71 secured to the wiper arm 56 engages the tail of pawl 69 to hold said pawl away from ratchet 70 when the motor 30 is in its lower or normal position. But upon the motor moving upward, the projection 71 leaves the tail of pawl 69 and said pawl becomes free to engage ratchet 70. The tail of the pawl 68 is normally engaged by a bar 72 secured to the top of a short stroke motor 73 supplied with compressed air thru a pipe 74. When the tail of pawl 68 is thus engaged, said pawl is held out of engagement with ratchet 70, but when the motor 73 operates to lift bar 72, pawl 68 falls into engagement with ratchet 70.

Shown at the lower right hand part of Fig. 1 is the apparatus which compose the motor switch of the selector. This switch has some of the characteristics of the well known side switch but is here called a motor switch because its most important functions involve the control of motors either directly thru a valve or indirectly thru magnetic devices. The stationary contacts of the motor switch are secured to a bracket 75 carried on the end bar 29. The wipers of the motor switch are secured on an irregular disk 76 pivoted at 77 to a plate 78 fast to the end bar 29.

Pivoted at 79 on plate 78 is a bell crank lever 80 which has one end resting on top of motor 81 and has on its other end a pawl 82 (Fig. 6) arranged to engage teeth on the

lower part of disk 76 to turn said disk on its pivot and thus shift the motor switch wipers from one set of stationary contacts to the next.

Pivoted at 83 is a pawl 84 arranged to engage teeth in the upper part of disk 76 and hold it in its advanced position when moved by motor 81 acting thru lever 80 and pawl 82. The pawl 84 is connected by a rod 85 to a bracket 86 secured to the shaft 35. The shaft 35 has a small longitudinal movement as represented by the collars 87 on each side of the end plate 29 as shown in Fig. 1.

The pawl 84 is not connected directly to the shaft 35, but to a sleeve 88 which is 80 slideable on said shaft and is connected to frame 41. Attached to the gear 48 is a case 89 in which is an ordinary clock spring acting to return the motor 42 to normal position when air is exhausted therefrom. In 85 such return, the pawl 84 strikes a small collar 90 on the end of shaft 35 to move said shaft to the left. Such longitudinal movement acts thru bracket 86 and rod 85 to lift pawl 84 from engagement with the teeth in the upper part of disk 76. When motor 42 moves from its normal position, the sleeve 88 slides on shaft 35 to carry pawl 84 away from collar 90, and spring 91 acting on pawl 84 moves the shaft 35 to the 95 right and permits said pawl to engage the teeth on disk 76.

A small motor 92 has an upwardly projecting rod 93 on which is a collar 94 which is in contact with the upper face of an arm 95 on bracket 86 (Fig. 7). A spring 96 on another part of the bracket acts to hold collar 94 and arm 95 in engagement with each other. The construction is such that when compressed air is supplied to the 100 motor 92, the shaft 35 is rocked to cause pawl 84 to engage the teeth of rack 33. When air is exhausted from motor 92, the shaft moves in the opposite direction to release pawl 84 from rack 33. 105

On the bell crank 80 is an arm 97 which extends up to valve casing 32. When the bell crank is in its normal position the arm 97 acts to open the valve so that compressed air can flow thru casing 32 and pipe 31 to motor 30. When the motor 81 acts to move bell crank 80, then the valve closes in casing 32 to shut off the supply to motor 30. 115

Pivoted at a convenient place near the motor switch is a lever 98, one arm of which 120 engages the stem of the valve in casing 99. A spring 100 presses the lever 98 against the pin of valve in casing 99 so as to normally hold said valve open and permit compressed air to flow thru casing 99 and pipe 101 to casing 32. On one of the motor switch wipers is a projection 102 adapted to engage the other arm of lever 98. When the motor switch is in either its normal or its second position, the projection 102 is 125 130

clear of lever 98, but when the motor switch reaches its third or final position the projection 102 engages lever 98 to move it away from the pin of valve in casing 99 and permit said valve to close.

Secured to the upper bar 27 is a slow magnet 103 whose armature 104 is on the shaft 38. When the magnet 103 is energized it rocks the shaft 38 to move pawl 37 into engagement with rack 36, and also to cause arm 46 to open valve in casing 45. Because magnet 103 is "slow" it holds its armature attracted during the sending of impulses due to operating the calling device at a local station.

Supported on the frame of the switch or at some other convenient place is a relay 105 (Fig. 11) which has two armatures and combines within itself and connected parts all of the functions of fast and slow line relays. Adjacent to the relay 105 is a valve casing 106, the valve stem of which bears against the armature 107 to hold it in its retracted position by reason of compressed air from a source or general supply entering the other end of the casing and acting to hold the valve closed. A spring 108 acts to hold the armature 107 against the valve stem, but the force of this spring is a little less than that required to open the valve. When the magnet is energized it attracts the armature 107 to open the valve in casing 106 and permit air to flow to pipe 109. After the armature is attracted, the circuit thru magnet 105 may be broken and remade under the conditions used in ordinary calling device operations. In other words, the valve in casing 106 and the spring 108 act to make relay 105 a slow relay as far as armature 107 is concerned.

The armature 110 has no such connections to it, and consequently responds to ordinary impulses sent thru 105. Relay 105 is a fast relay as far as armature 110 is concerned.

45 The subscriber at his local station is connected by line wires to a line switch at the central office.

By the operations of his line switch the subscriber has his line wires extended to lines 50 117 and 118 to this switch. Hence, wires 117 and 118 become line wires leading to a local station and over which the subscriber may send impulses by operating his calling device. The first circuit coming to this switch comes to line 111 and then continues thru 112—contact arm 113—114—115 to battery X. Battery X is a common battery, and the circuit just given in part starts from the other side of this battery and goes thru a magnet 55 on the line switch to connect the lines 117 and 118 to the local station. This circuit belongs to the line switch and is referred to here only because part of it appears in this switch.

65 When a subscriber operates his calling

device after being connected to this switch a circuit is completed as follows: Battery X—resistance 116—117 to local station and back over 118—relay 105—119—X.

This circuit thru relay 105 attracts armature 107 to open the main valve 106 to permit compressed air to flow from the source to the local supply pipe 109. From pipe 109 air flows to motor 92 which rocks shaft 35 so that holding pawl 34 may fall into ratchet 33. It also flows to motor 73 which lifts bar 72 so that holding pawl 68 may fall into ratchet 70.

When armature 107 was attracted it closed springs 120 and 121 to make a new circuit 80 from the line switch over wire 122 to take the place of the circuit over wire 111 which becomes broken at 112—114 by the first advance of the motor switch. The closure of springs 120 and 121 also close a circuit as follows: X—120—121—123—124—slow magnet 103—125—126—65—64—127—X. 85

The attraction of armature of magnet 103 tilts shaft 38 to open valve 45 which permits air to flow to the small quick motor 81 and to the horizontal motor 42. Motor 42 cannot operate as it is held by connections to escape wheel 50 and can move only when the magnet 53 operates. But the motor 81 operates on the bell crank 80 to shift the motor switch arms from normal position to the next adjacent position, and also to permit the normally open valve 32 to close. When armature 107 opened valve 106 as before described, air flowed thru 109, normally 100 open valve 99 and pipe 101 to valve 32. From here it would flow thru pipe 31 to operate motor 30, but the quick movement of motor 81 permits valve 32 to close and cut off the flow at this point. 105

What has just been described is what results from the attraction of the slow armature 107 upon the first impulse being sent thru relay 105. One of the things done is advancing the motor switch one step. This would close a circuit for the magnet 53 if it were not for the fact that the fast armature 110 operates at the same time to open springs 128 and 129. But upon breaking the circuit at the local station, armature 110 falls back 115 and a circuit is completed as follows: X—128—129—130—131—switch arm 132—133—134—53—123—121—120—X.

Impulses sent over this circuit operate the escapement to let the motor 42 move the 120 motor 30 and its connected wipers step by step to positions under successive rows of contacts shown in the upper part of Fig. 11. The number of steps the escapement makes is determined by the number of impulses 125 which the subscriber at his local station sends by operating his calling device. Upon making the first step, the pin 66 leaves the arm 62 so that roller 63 falls to contact with escape wheel 50 and opens contact 130.

springs 64 and 65. Each tooth passing roller 63 closes these springs, but they are left open at the termination of the last step. The springs 64 and 65 are in the circuit for the magnet 103, but as this is a slow magnet its armature remains attracted during the stepping of the escapement. But upon the stoppage of the motor 42, the open condition of these springs permanently breaks this circuit thru magnet 103, and its armature falls back to permit valve 45 to close.

The closure of valve 45 shuts the compressed air from motors 42 and 81 and opens the exhaust. Owing to the fact that the pawl 68 had previously engaged ratchet 70, the exhaust from motor 42 does not permit that motor to return to its normal position at this time. For operative purposes, a check valve 43* (Fig. 1) is placed in the pipe 43 so as to cause the exhaust from motor 42 to be gradual instead of sudden.

But the exhaust from 81 is immediate with the result that the bell crank 80 falls back and opens valve 32. When motor 42 made its first movement to the right, the shaft 35 and connection 86 also moved to the right to permit holding pawl 84 to fall into the upper teeth of disk 76. As a result the motor switch is held in its moved position after the bell crank 80 has fallen back.

Opening the valve 32 permits compressed air to flow thru 109—99—101—32—31 to motor 30. This starts the motor 30 to carry its wipers upward on a trunk hunting expedition. As in some well known constructions, idle trunks have battery connections to them so that when the wipers come to the bank terminals of such a trunk a current will flow as follows: Battery connection 135—found contact point 136—wipers 59—125—magnet 103—124—123—121—120—battery X.

Energizing magnet 103 tilts shaft 38 to throw pawl 37 in ratchet 36 and stop motor 30 with its wipers in contact with the found trunk. The tilting of shaft 38 also opens valve 45 to permit compressed air to flow to motors 42 and 81. Air flowing to motor 42 does nothing at this time because magnet 53 does not operate, but motor 81 acts to shift the motor switch to its final position and to permit valve 32 to close.

The closure of valve 32 permits air to exhaust from motor 30, but as the holding pawl 34 is in engagement with ratchet 33 by reason of compressed air being in motor 92, exhausting air from motor 30 accomplishes nothing at this time. The final movement of the motor switch moves lever 98 so that valve 99 may close and cut the supply of air from valve 32.

When the wiper 59 came to engagement with the idle contact point 136, the wipers 60 and 61 came to contact points 137 and 138 connected to wires 139 and 140 leading

to the next switch which may be either a selector or a connector. At the time the motor switch was shifted to its final position it connected the line wires 117 and 118 to wipers 60 and 61 and hence to wires 139 and 140 so that thereafter these wires become line wires leading back to the calling local station. The completed connections thru this switch are as follows: 117—141—142—arm 113—143—144—61—138—140; and 118—contact points closed by arm 132—146—60—137—139.

When the wipers reach an idle trunk, the switch at the end of that trunk (selector or connector) moves to break the battery connections to 135. This breaks the circuit thru magnet 103 so that shaft 38 may return to its normal position. This permits stopping pawl 37 to become free from ratchet 36, but as compressed air had previously been cut off from motor 30, this accomplishes nothing.

The return of the shaft 38 to its normal position lets valve 45 close to cut off compressed air from motors 42 and 81. Nothing happens at motor 42 because pawl 68 is in engagement with ratchet 70 by reason of compressed air being on motor 73. It should be noticed that pawl 69 is also in engagement with ratchet 70 by reason of the fact that the upward movement of motor 30 had lifted the projection 71 from the tail of pawl 69. Pawl 69 will hold until motor 30 returns to normal position, which is after pawl 68 has been released by the exhaust of air from motor 73. This will appear later.

Cutting the air supply from motor 81 lets bell crank 80 return to normal position and open valve 32. But as valve 99 had been previously closed by reason of the motor switch moving lever 98, nothing results from the opening of valve 32. And as pawl 84 is still in engagement with ratchet 76, the motor switch is retained in its advanced position when the bell crank 80 falls back.

During subsequent operations in making a call, and during talking, the relay 105 is the only electrical device on this switch which continues to receive current. By examining the circuits it will be seen that this relay is bridged between wires 117 and 118, and that the circuit for the relay will be broken when the calling subscriber breaks connection between the wires by hanging up his receiver. Current flowing thru relay 105 maintains its armature 107 attracted to hold open valve 106 and keep air pressure in pipe 109. Small motors 73 and 92 connected to this pipe are the only motors which take air pressure during talking.

When the calling subscriber breaks the connection between 117 and 118, the armature 107 falls back so that valve 106 may shut off the air supply from 109. When this

- occurs motors 73 and 92 fall back to normal position. In doing this, bar 72 of motor 73 lifts pawl 68 from ratchet 70, and motor 92 permits pawl 34 to fall out of ratchet 33.
- 5 When this occurs motor 30 falls back to its lowest position and causes projection 71 to release pawl 69. With pawls 68 and 69 both released, the spring in case 89 returns motor 42 to normal position, carrying the parts in 10 frame 41 with it. As these parts approach their normal position, pawl 34 strikes collar 90 on shaft 35 to move said shaft to the left and release pawl 84. When this occurs, spring 76* (Fig. 6) returns the 15 motor switch to its normal position.

For the purpose of making the general operation more understandable, I will give a brief review of what has preceded.

The first impulse coming to this switching mechanism passes thru the line relay (magnet) 105 to attract its armature 107 so as to open valve 106 and admit compressed air to the local supply pipe 109. As a consequence of this, motors 73 and 92 are 25 operated to bring the holding pawls 68 and 34 into operative position. As motors 73 and 92 always operate simultaneously they may be considered as simply duplicate representatives of the same thing in the same 30 sense that the same battery is frequently shown at several places on the same drawing.

The same impulse thru relay 105 also closes contacts 120—121 for magnet 103 35 which in turn opens valve 45 and admits air from pipe 109 to motors 42 and 81.

The motor 81 closes valve 32 so as to intercept the flow of air to motor 30, and at the same time it shifts the motor switch to 40 make a circuit for magnet 53 so that other impulses thru relay 105 will cause magnet 53 to release motor 42 step by step.

When this stepping stops, circuit is broken for magnet 103 at springs 64—65, and valve 45 closes. This causes motor 81 to fall back so as to open valve 32 and start motor 30 upward.

When an idle trunk is found, a new circuit is completed for magnet 103 to again 50 open valve 45 and cause motor 81 to again shift the motor switch.

Motors 42 and 30 are switch moving motors. Motor 81 is a circuit shifting motor which also controls valves for motor 55 30. Motors 73 and 92 are pawl motors.

The motors herein described may be made very cheaply and will operate a long time without attention or repairs if it is not necessary to fit them accurately to prevent 60 leakage. The valves herein described are of the self-closing type, and it is to be observed that valve 106 is opened to admit compressed air to the local supply pipe 109 only when the switching mechanism is 65 called into operation. At all other times

the valve 106 is closed and it is not possible for losses to occur by leakage when the switch is idle. During operation, compressed air is admitted to the main motors 42 and 30 only during brief intervals, and 70 is continuously used only for pawls 34 and 68. Because of the valve arrangements, leakage at the motors becomes a negligible quantity.

What I claim is:

1. In a switching mechanism having power devices for moving parts of the mechanism in directions perpendicular to each other, pawls designed to hold such movement when made but normally in inoperative positions, pneumatic devices for controlling the operative condition of said pawls, a valve for admitting compressed air to said pneumatic devices, and a magnetic device for controlling said valve. 75 80 85

2. Power devices for moving a switching mechanism, holding pawls, pneumatic devices for bringing said pawls into operative position, and means for controlling the flow of air to and from said pneumatic devices. 90

3. A pneumatic motor, an escapement for controlling the movements of said motor, a relay, and means by which said relay simultaneously controls the operations of said escapement and the supply of air to said 95 motor.

4. The combination with a pneumatic motor, and an escapement by which the motor is controlled, of a relay having two armatures, means by which one armature 100 controls the supply or air to the motor, and means by which the other armature controls said escapement.

5. A supply pipe provided with air under pressure, a pneumatic motor, a valve arranged to permit air to flow from the pipe to the motor, a magnet for operating the valve, an escapement for controlling the movements of the motor, and means operating thru stoppage of escapement movements for breaking the circuit, for said magnet. 105 110 115

6. A pipe, a switch operating motor and other pneumatic devices connected to said pipe, means for admitting compressed air 115 to said pipe so that it may flow to the devices connected thereto, and means operated by the admitted air for intercepting the flow to the motor before said motor can 120 operate.

7. In a switching mechanism, a pipe having branches leading to a plurality of devices, means for admitting compressed air to said pipe, and quick operating means in one branch for intercepting the flow of compressed air to another branch. 125

8. In a switching mechanism, electrical and pneumatic devices for operating said mechanism, a motor switch serving to control both electrical circuits and the flow of 130

- air to pneumatic devices, and a pneumatic motor for operating said motor switch. 65
9. In a switching mechanism, a supply pipe, a valve for admitting compressed air to said pipe, a pneumatic motor connected to a branch of said pipe, a relay, and means by which a series of impulses flowing thru said relay will hold said valve open and control a step by step movement of said motor. 70
10. Wipers, a pneumatic motor for moving said wipers, an escapement for causing said motor to make its movements step by step, a magnet for operating said escapement, and a relay for controlling said magnet and the supply of air to said motor. 75
11. A pneumatic motor, a magnet serving to open a communication for compressed air to operate the motor, and an escapement controlling the movements of the motor and the circuit for the magnet. 80
12. In a switching mechanism, a pneumatic motor for moving the mechanism in one direction and a second pneumatic motor for moving it in another direction, a source of compressed air having connections to both motors, valves in said connections serving to control the supply of air to the motors, a magnet having an armature, and means by which a change in the position of the armature will change the valves so as to shift the open connection from one motor to the other. 85
13. In a switching mechanism, two pneumatic motors provided with connections to a source of compressed air, valves arranged to control the open and closed conditions of said connections, and a magnet arranged to alternately open and close said valves. 90
14. In a switching mechanism, two pneumatic motors provided with connections to a source of compressed air, and a magnet arranged to alternately open and close said connections. 95
15. In a switching mechanism, two pneumatic motors provided with connections to a source of compressed air, a magnet arranged to alternately open and close said connections, and means for controlling said magnet by the parts moved by said motors. 100
16. In a switching mechanism, two pneumatic motors, a locally energized magnet arranged to control said motors so as to cause them to operate in succession, and means for controlling said magnet from parts moved by said motors. 110
17. In a telephone exchange, the combination with switching mechanism, pneumatic motors for operating the mechanism, a supply pipe, and valves for admitting air from a pipe to the motors, of a special valve normally cutting said supply pipe from a general source of compressed air, and electrical devices for opening said special valve. 115
18. The combination with a relay, and a pipe for conveying compressed air to pneumatic devices, of a valve controlling the supply of air to the pipe and the operations of the armature of the relay when electrical impulses flow thru said relay. 120
19. In a switching mechanism operated by pneumatic devices and controlled by a relay, a valve serving when closed to cut the pneumatic devices from a source of air pressure and serving when closed to control the armature of said relay. 125
20. In a switching mechanism, wipers, pneumatic motors for moving said wipers in directions perpendicular to each other, a supply pipe for said motors, and means for connecting said motors successively to said supply pipe. 130
21. In an automatic trunk selecting system, a pneumatic motor associated with each trunk, a source of compressed air, and automatic means controlled through the selected trunk for admitting air to a motor upon the selection of the associated trunk. 135
22. In an automatic trunk selecting system, a pneumatic motor associated with each trunk, a source of compressed air, means by which upon a trunk being selected air from the source will be automatically admitted to the associated motor, and a restraining device for said motor. 140
23. In a trunk selecting system, having a switching mechanism connected to each trunk, a pneumatic motor associated with each switching mechanism for moving it from normal position, a source of compressed air, and automatic means controlled through the selected trunk for admitting air to a motor upon the selection of the associated trunk. 145
24. In a trunk selecting system, having a switching mechanism connected to each trunk, a pneumatic motor associated with each switching mechanism for moving it from normal position, a source of compressed air, automatic means controlled through the selected trunk for admitting air to a motor upon the selection of the associated trunk, and a restraining device for holding said mechanism against movement by said motor. 150
25. In a trunk selecting system, having a switching mechanism on each trunk, pneumatic means for moving the switching mechanism, a source of compressed air, and automatic means controlled through the selected trunk for applying the air to move a mechanism upon the selection of the associated trunk. 155
26. In a trunk selecting system, having a switching mechanism on each trunk, pneumatic means for moving the switching mechanisms, a source of compressed air, automatic means controlled through the selected trunk for applying the air to move a mechanism upon the selection of the as- 160

sociated trunk, and a restraining device for holding the mechanism against such movement.

27. In a trunk selecting system having a switching mechanism on each trunk, automatic means controlled through the selected trunk for putting a strain upon a mechanism to move it from normal position upon the selection of the associated trunk, and an escapement for controlling the movement due to such strain.

28. In a trunk selecting system having a switching mechanism on each trunk, automatic means for putting a strain upon a mechanism to move it from normal position upon the selection of the associated trunk, and means for controlling such movement from a distant station.

29. In a trunk selecting system having a switching mechanism on each trunk, automatic means for putting a strain upon a mechanism to move it from normal position when the associated trunk is selected, an escapement for controlling the movement due to such strain, and means for controlling the escapement from a distant station.

30. In a trunk selecting system having a switching mechanism on each trunk, a source of compressed air, automatic means for applying the pressure of the air to a mechanism to move it when the associated trunk is selected, an escapement arranged to hold the mechanism against movement by the air pressure, and means for controlling said escapement by electrical impulses flowing over the selected trunk.

31. In a switching mechanism, a pneumatic motor, an escapement for permitting said motor to advance step by step, and a magnet operated by electrical impulses from a distant station for controlling said escapement.

32. In a switching mechanism, a wiper carriage, a motor for moving said carriage, a rack and pinion for controlling the movement of said carriage, and an escapement for controlling the rotation of the pinion.

33. In a switching mechanism, a wiper carriage, a motor for moving said carriage, a rack and pinion for controlling the movement of said carriage, an escapement for

controlling the rotation of the pinion, and an electromagnet for controlling said escapement.

34. In a switching mechanism, a wiper carriage, a pneumatic motor for moving said carriage, a rack and pinion for controlling the movement of said carriage, and an escapement for controlling the rotation of said pinion.

35. In a switching mechanism, a wiper carriage, a pneumatic device for moving said carriage, a switch for controlling the electrical circuits of said mechanism, and a pneumatic motor for controlling the operation of said switch and said device.

36. In a switching mechanism, a wiper carriage, a pneumatic device for moving said carriage, a switch for controlling electrical circuits of said mechanism, and a pneumatic motor which operates in one manner for operating said switch and in another manner for controlling the operation of said carriage.

37. In a switching mechanism, a wiper carriage, a pneumatic device for moving said carriage, a switch for controlling electrical circuits of said mechanism, a pneumatic motor which operates in one manner for operating said switch and in another manner for controlling the operation of said carriage, and an electro magnet for controlling the operation of said motor.

38. An automatic switch, a ratchet wheel for controlling the operation of said switch, a magnet for controlling said switch, a circuit for said magnet, a pair of springs in said circuit operated by said ratchet wheel to control the circuit of said magnet.

39. In a telephone system, an automatic switch, an incoming trunk individual to said switch, outgoing trunks accessible to said switch, wipers on said switch normally disconnected from said incoming trunk, means for operating said switch to select an idle one of said outgoing trunks, an auxiliary switch in said switch for connecting said wipers to said incoming trunk after said switch has selected said idle trunk, and a pneumatic device for controlling the operation of said switch and said auxiliary switch.

FRANK A. LUNDQUIST.
